CALLOUS REMOVER

Richard Ihasz, Stratford, Conn., assignor to Sperry
Rand Corporation, New York, N.Y.

Filed June 21, 1971, Ser. No. 155,405

Term of patent 14 years

Int. Cl. D28—03
U.S. Cl. D86—10 C

Fig. 5.

Fig. 6.

FIG. 1 is a perspective view of the callous remover showing my new design;

FIG. 2 is a top plan view of FIG. 1;
 FIG. 3 is a side elevation of FIG. 1;
 FIG. 4 is a front elevation of FIG. 1;
 FIG. 5 is a rear elevation of FIG. 1; and
 FIG. 6 is a bottom plan view of FIG. 1.

I claim:

An ornamental design for a callous remover, as shown.
